UNITED STATES PATENT OFFICE.

JOHN W. ALBRIGHT, OF BURLINGTON, IOWA.

NECK-YOKE CENTER.

SPECIFICATION forming part of Letters Patent No. 406,250, dated July 2, 1889.

Application filed November 14, 1888. Serial No. 290,826. (No model.)

To all whom it may concern:

Be it known that I, JOHN W. ALBRIGHT, a citizen of the United States, residing at Burlington, in the county of Des Moines and State 5 of Iowa, have invented certain new and useful Improvements in Neck-Yoke Centers; and I do hereby declare the following to be a full, clear, and exact description of the invention, such as will enable others skilled in the art 10 to which it appertains to make and use the same.

My invention relates to neck-yoke centers, and has for its object to provide a center which will allow an easy movement of the 15 pole in all directions. In centers of this general style the constructions are such that the wear upon the parts is unequal, thereby weakening the parts and increasing the liability of breaking, also causing much annoyance 20 occasioned by the rattling of the parts. I overcome these objections by constructing a neck-yoke center composed of an outer ring provided with two horizontal pivot-points engaging eyebolts in the yoke, and a pole-ring 25 vertically pivoted in the said outer ring at points diametrically opposite each other, whereby I compensate for all vertical and lateral motion of the pole due to the unevenness of the travel of the horses and to the 30 wheels of the vehicle striking obstructions in the road; also by providing the outer ring with rounded projections, against which the inner ring bears independent of its pivotal points, thereby relieving the pivots of excessive strain.

35 I will now proceed to describe my invention more fully in connection with the accompanying drawings, wherein—

Figure 1 is a perspective view of part of a 40 neck-yoke with my invention applied thereto. Fig. 2 is a vertical central cross-section of the same. Fig. 3 is a front elevation of a modification.

45 The same letters of reference indicate identical parts in all the figures.

In the drawings, A represents the neck-yoke, and B the outer and C the inner or pole ring. The yoke is provided with two eyebolts D D, the shanks of which pass through 50 the yoke and are rigidly secured therein in

any suitable manner. The outer ring B is provided with two pivotal points E E, adapted to engage the eyes of the bolts D D, said pivotal points having shoulders e e, which bear against the eyebolts D D. The inner face of 55 the ring B is provided with seats G G vertically and diametrically opposite each other, said seats having rounded projections F F. The inner or pole ring C is provided on its outer face with two enlargements or bosses 60 g g, adapted to fit in the seats G G and bear against the projections F F, said pole-ring being pivoted in the seats G G by means of pins H H passing into the outer ring B, and secured therein in any suitable manner. 65

In order to prevent the rattling of ring C on the pole and prevent the wearing of the pole, I line said ring with leather or any suitable material.

I have shown and described the rounded 70 projections F F as being only on one side of the ring B; but, if found desirable, I may provide both sides of said ring with the rounded projections.

By the construction hereinbefore described 75 it will be seen that in holding back the vehicle the pole-ring will press against the rounding projections F F independent of the pivot-pins H H, and thereby relieve the pins of excessive strain. 80

In the modification shown in Fig. 3 I have omitted the rounding projections F F on the outer ring and simply provided it with seats or enlargements g g, through which the pivot-pins pass. 85

What I claim, and desire to secure by Letters Patent, is—

1. The combination, with a neck-yoke, of two eyebolts secured thereto, a ring horizontally pivoted in the eyes of said bolts, and a 90 pole-ring vertically pivoted at diametrically-opposite points in said outer ring, substantially as described.

2. The combination, with a neck-yoke, of two eyebolts secured thereto, a ring having 95 two shouldered projections formed thereon and pivoted in the said eyebolts, two projections F F, formed on the front face of said ring, said projections being concaved on their rear faces, and a pole-ring pivoted in the outer 100

ring and having bosses thereon which bear against the concaved faces of the said projections F F, substantially as described.

3. The combination, with a neck-yoke, of 5 two eyebolts secured thereto, a ring pivoted in said eyebolts, and a pole-ring vertically pivoted in said outer ring, said pole-ring having enlargements bearing against projections on the outer ring, substantially as described.

In testimony whereof I affix my signature in 10 presence of two witnesses.

JOHN W. ALBRIGHT.
